J. HEGEDUS

INTERCHANGEABLE SHOE HEEL

Filed July 27, 1927

Fig. 1

UNITED STATES PATENT OFFICE.

JOSEPH HEGEDUS, OF COLLEGE POINT, NEW YORK.

INTERCHANGEABLE SHOE HEEL.

Application filed July 27, 1927. Serial No. 208,689.

This invention relates to a detachable heel, and its object is to provide an article of this character having means to secure the same, when in position on a shoe, and to permit of 5 its easy and quick removal for replacement, or other purposes.

Other objects, are neatness of appearance and efficiency and durability in service.

The universal practice of wearing rubber, 10 or cushion heels, has created the necessity for different means for their attachment than that which is commonly employed in heels of all leather construction, but these means have for the most part consisted of a method of permanent fixation, that is, the heels 15 are usually so affixed as to be removable only by a complete disruption and tearing off from the body of the shoe.

This device, by a novel mechanical construction, 20 makes it possible to remove the heel by the mere throwing of a lever and a slight sliding motion of the cushion element. It is thus an easy and simple matter to remove a worn cushion element and replace 25 it with a new one whenever desired.

The device will be found fully described in the following specification and claim, and illustrated in the accompanying drawings, in which:

30 Fig. 1 shows a shoe illustrating the appearance of the heel as attached thereto.

Fig. 2 shows a top plan view of the upper, or permanent heel with the cushion element partly slid out from its under side, it being 35 in the first position of the process of attachment, and with the locking lever open.

Fig. 3 shows a section on the line 3—3 of Figure 2.

Fig. 4 shows the heel with the cushion element in its final position and the lever thrown over to lock same.

Fig. 5 shows a section on the line 5—5 of Figure 4.

Fig. 6 shows a section on the line 6—6 of Figure 4.

Fig. 7 shows another form of the invention having a slidable stop member mounted on the locking lever.

Fig. 8 shows a section on the line 8—8 of Figure 7.

Referring first to Figure 1, the heel 10 having a base element 11 and a cushion element 12, is shown attached to a shoe of conventional design 13. Referring now to Figure 2 especially, and to Figure 3 in conjunction therewith, the device comprises the

base element 11 to which is secured the plate 14 by means of the screws as seen at 15, 16 etc., which are driven upward into the said base element as seen best in Figure 6. Still 60 referring to Figures 2 and 3, lock slots as seen at 17, 18 etc., and which are in shape, large apertures with narrow extensions therefrom, are located near to the outer margin of the plate. 65

A locking lever 20 is pivotally secured to the plate as shown at 21. This is provided with a hook member 22. A V opening 23 in the plate permits of the swing of the lever. The said plate and lever are preferably of metal. 70

The cushion element 12, which is preferably of rubber or like resilient material, is provided with button studs which may be also of metal. These are seen best in figure 75 3 at 25 and 26.

When it is desired to attach the cushion element, it is placed over the base so that the button studs penetrate the lock slots through the larger portions thereof, the lever being open as seen in Figure 2. The cushion element is then slid forward so that the stud heads engage the slot extensions and the said element is in its final position, the lever is then thrown over as illustrated 85 in Figure 4 and its hook member engages the rear stud and securely locks the whole.

In the form of the invention shown in Figures 7 and 8, additional hooks 28 and 29 are provided and a slidable stop element 30 90 is mounted on the shank of the lever 20. This stop element, when in its forward position as illustrated, rides up on the plate extension 31 and engages a recess 32 in the cushion element as seen in Figure 8. The 95 said stop element is provided with side members as seen at 33 and 34 in Figure 8, which engage the sides of the lever. It is secured by a pin 34 passing through a slot 35 seen in Figure 7, and is also provided with a raised 100 portion 36 as illustrated.

Having thus described my invention, what I claim as new and desire to secure by Letters Patent, is as follows:

A detachable heel for shoes comprising a 105 base portion having a recess therein, a plate mounted on said base portion disposed over said recess having key hole apertures therein, said key hole apertures each comprising an enlarged rearward portion and a constricted forward portion, a resilient heel member mounted on said plate, headed studs 110

on said resilient heel portion each adapted to be disposed through the enlarged rearward portion of one of said keyhole apertures, a lever disposed in said recess and pivotally attached to said plate comprising a hooked extremity adapted to engage one of said studs for retaining the same in the constricted portion of that keyhole aperture into which it extends after the resilient heel mem-

ber has been moved forwardly, and locking mechanism comprising a bracket slidably mounted on said lever adapted to be engaged in a recess in said resilient heel member for retaining said lever in a predetermined position. 10

15 In testimony whereof I have affixed my signature.

JOSEPH HEGEDUS.
